UNITED STATES PATENT OFFICE.

CLARK ROBERTS, OF WINCHESTER, ILLINOIS.

IMPROVEMENT IN LATCHES FOR GATES AND OTHER PURPOSES.

Specification forming part of Letters Patent No. 136,183, dated February 25, 1873.

To all whom it may concern:

Be it known that I, CLARK ROBERTS, of Winchester, in the county of Scott and State of Illinois, have invented a new and useful Improvement in Gate-Latches; and I do hereby declare that the following is a full, clear, and exact description thereof, reference being had to the annexed drawing making part of this specification, in which—

Figure 1 is a front elevation of a gate provided with my improved latch or fastening. Figs. 2 and 3 are detail views, on an enlarged scale, of my improved latch.

The same letters of reference are employed in all the figures in the designation of identical parts.

This invention consists of certain improvements on the gate-latch patented by me February 5, 1867—namely, in forming an aperture in the laterally-projecting portion of the latch, through which one arm of the thumb-piece or lever may pass to the arm of the latch, and oscillate the latter in unlocking the gate.

To enable those skilled in the art to make and use my improvements, I will now proceed to describe, specifically, their construction and operation.

The gravitating-latch is an angular piece of metal, which is suspended from a suitable pivot upon the post or jamb of the gate or door by its vertical member A. Its member B projects at an angle of one hundred and thirty-five degrees, or thereabout, and has the form of an isosceles triangle, the base of which is at the junction with the member A. Thus constructed it may be applied both to left-handed or right-handed gates or doors. The latch must be so hung upon the post or jamb as that the member B, when the latch is in a state of rest, will project at one end of its base a sufficient distance to overlap and thus confine the gate or door when shut. All the angles of the member B are rounded, as shown, to facilitate the oscillation of the latch by the gate in closing it. The latch is limited in its oscillation by a segmental bar or guide, C, merging with its ends in the side bars d and d¹ of a triangular frame, D. From the apex of the triangular member B of the latch extends an arm, B', obliquely to and hooks

under the guide C, as best seen in Fig. 2, so that the vibrations of the latch are checked by the arm B' coming in contact with the bars d d¹ at the ends of the guide. The latter also serves the very useful purpose of steadyng the latch, and diminishing the strain upon the axis upon which it swings. The frame D, which is securely fastened to the post or jamb, is constructed with special reference to the formation of the latch, and it has near its upper termination a tubular projecting stud or nipple, d², which serves as the pivot upon which the latch oscillates. This nipple extends so far into the eye of the latch that the head of the screw E, while confining the latch against withdrawal from its pivot, will not bear against the latch, but against the end of the nipple, thus allowing the latch to vibrate freely. The thumb-piece or disengaging-lever F may be attached to the gate or door in the manner indicated in Fig. 1, but I prefer to attach it also to the post or jamb; and in order that, thus disposed, it may properly operate upon the latch, I form an aperture, b, in the member B of the latter, through which one arm of the thumb-piece passes, to rest against one side or the other, according as the latch is employed with a right-handed or left-handed gate or door, of the arm B'. The thumb-piece is pivoted in manner like the latch, and it also is so constructed that it may, together with the latch, be used in connection with both right-handed and left-handed gates and doors.

What I claim as my invention, and desire to secure by Letters Patent, is—

The combination of the gravitating-latch and the thumb-piece, the former being constructed with an aperture, b, and arm B' underneath it, and one arm of the latter passing through said aperture to operate upon arm B', substantially as specified.

In testimony that I claim the improvement herein described I have hereunto subscribed my name this 25th day of November, 1872.

CLARK ROBERTS.
